[57] **CLAIM**

The ornamental design for a facade for enclosing data processing apparatus or the like, as shown and described.

DESCRIPTION

FIG. 1 is a left side, top and front perspective view of the facade for enclosing data processing apparatus or the like showing our new design;

FIG. 2 is a left or a right side elevation of the same;
FIG. 3 is a right side, bottom and rear perspective view of the same;

FIG. 4 is a cross-sectional view of the same at position determined by the arrows in FIG. 3;

FIG. 5 is a perspective view of the right-most front panels of the same; and

FIG. 6 FIG. 7, FIG. 8, and FIG. 9 are right, rear and top perspective views of the same illustration configurations resulting from changes in the various number of panels comprising the facade.
